VEHICLE

John C. Trotter, Niagara Falls, N. Y., assignor to
Bell Aircraft Corporation, Wheatfield, N. Y.

Application March 10, 1948, Serial No. 145,013

Term of patent 14 years

(Cl. D14—3)

To all whom it may concern:

Be it known that I, John C. Trotter, a citizen of the United States, residing at Niagara Falls, in the county of Niagara and State of New York, have invented a new, original, and ornamental Design for a Vehicle, of which the following is a specification, reference being had to the accompanying drawing, forming part thereof.

Fig. 1 is a side elevational view of a vehicle, showing my design;

Fig. 2 is a top plan view thereof;

Fig. 3 is a front end elevational view thereof;
and

Fig. 4 is a rear end elevational view thereof.
The characteristic features of my design reside in the portions shown by means of full lines in the drawing.

I claim:

The ornamental design for a vehicle, as shown and described.

JOHN C. TROTTER.
